L. C. BILLINGS.
CHICKEN BROODER.

No. 531,255.

Patented Dec. 18, 1894.

UNITED STATES PATENT OFFICE.

LOUIS C. BILLINGS, OF MILFORD, NEW HAMPSHIRE, ASSIGNOR TO THE L. C. BILLINGS COMPANY, OF SAME PLACE.

CHICKEN-BROODER.

SPECIFICATION forming part of Letters Patent No. 531,255, dated December 18, 1894.

Application filed May 7, 1894. Serial No. 510,354. (No model.)

To all whom it may concern:

Be it known that I, LOUIS C. BILLINGS, a citizen of the United States, and a resident of Milford, in the county of Hillsborough and 5 State of New Hampshire, have invented certain new and useful Improvements in Chicken-Brooders; and I do hereby declare that the following is a full, clear, and exact description of the invention, which will enable others 10 skilled in the art to which it appertains to make and use the same, reference being had to the accompanying drawings, which form a part of this specification, and in which—

Figure 1 is a perspective view of my improved "chicken-brooder" as it appears when in use; one of the doors being shown open and the tray, or false bottom, being extended. Fig. 2 is a longitudinal sectional view of the same, on the vertical plane indicated by the 15 broken line marked $x-x$ in Fig. 5. Fig. 3 is a transverse sectional view through the brooder, on the vertical plane denoted by the broken line marked $x'-x'$ in Fig. 2. Fig. 4 is a longitudinal sectional view through the 20 brooder on line $y-y$ in Fig. 5. Fig. 5 is a sectional view on the horizontal plane indicated by the broken line marked $y'-y'$ in Fig. 4; and Fig. 6 is a detail view of the thermostat, and the mechanism connected therewith, for automatically regulating the heat in 25 the brooding chambers.

Like letters of reference designate corresponding parts in all the figures.

My invention relates to apparatus for 30 "brooding" artificially hatched chickens; that is to say: raising strong and healthy chicks after these have been hatched artificially in the incubator. Experience has abundantly demonstrated that it is easier to 35 hatch healthy eggs in a properly constructed and well-managed incubator, or hatching apparatus, than to raise and develop the chicks after they have been hatched, when their frail and delicate condition imperatively demands 40 uniformity and evenness of heat, proper ventilation, and absolute cleanliness. In order to attain these necessary requirements, I have invented a brooder or apparatus designed especially for brooding the chicks after these 45 have been artificially hatched, which is so constructed that the heat in the brooding-

chambers will be regulated automatically, resulting in a perfectly even temperature at all times; and also provided with ventilating and cleaning devices by the aid of which equally 55 important conditions of fresh and pure air, and absence of dirt and foulness are made attainable with a minimum of labor on the part of the attendant, and a maximum of comfort and benefit to the brood of young chicks 60 which is being raised in the apparatus.

On the accompanying two sheets of drawings, the reference-letter A denotes the bottom of my improved brooder; B, the sides or end pieces of the same; C, the top, and D the 65 stationary or upper part of the front side, the lower part of which consists of two or more slanting or outwardly-inclined doors D' D', swinging on hinges d d and having glass panels to admit light into the brooding-chambers 70 or compartments E E, of which there may be two or more; or, if desired, a brooder may be constructed consisting of only a single compartment.

In practice, I prefer to make my improved 75 brooder about three feet in length, two feet wide, and eighteen inches high; that being a very convenient and popular size; but it will be obvious that it may be made to order of any size or dimensions desired, without departing from the spirit of my invention; the size of the apparatus being simply a matter of convenience and expediency.

The vertical back F is provided with openings e e one for each compartment E which 85 may be closed by a flap F', swinging on hinges f f, so as to form when open, as shown in dotted lines in Fig. 4, an inclined plane or platform leading from the openings e e, and facilitating egress from and ingress into the brood- 90 ing compartments.

In the present illustration of my improved brooder, I have shown an apparatus comprising two brooding-chambers or compartments, E, E; but there may be three or even a larger 95 number, if desired, according to the capacity which the apparatus is to have. These compartments are separated by a vertical wire screen partition G, which does not, however, extend all the way up to the under side of the 100 water-tank H, the bottom h of which forms the roof the brooding compartments E E, but

leaves a narrow open space *g* between the top of partition *G* and the bottom of tank *H*, so that the air heated by contact with the hot bottom of the water-tank may circulate freely 5 and without obstructions through and between the compartments *E E*. The tank *H* (which is made, preferably, of galvanized sheet-iron) is supported firmly upon two (or more) parallel slats *I I*, running longitudinally 10 through the apparatus a suitable distance below the top or roof *C* of the same, and resting at opposite ends upon cleats which are fastened on the inside of the end-pieces *B B*.

The water-tank *H* is a closed receptacle or 15 reservoir, resting upon the slats *I I* in the top of the apparatus above the hinged glass doors *D' D'* and rear openings *e e*; but smaller than the apparatus, so as to leave an open air-space, *a*, all around the tank, on all sides thereof, 20 and also an air-space *a'*, between the top *h'* of the tank and the roof *C* of the apparatus. The tank may be filled with water by means 25 of a pipe *J*, which extends up through the roof *C*, and this water is heated by means of an interior flue *K*, which enters tank *H* at one end, and is, at its other end, deflected upwardly so as to form a chimney or outlet *k*, for 30 the products of combustion after these shall have given off the greater part of their heat to the water in the tank.

That end of the heating flue *K* which passes out through one of the end pieces *B* is connected to the chimney *K'* of a lamp or heating apparatus *L*, which may be of any approved construction, and rests upon an adjustable shelf or bracket *M*, attached to the outside of the end-piece *B*. This heating apparatus (unless adapted to be used with gas, in which case the oil reservoir is, of course, 35 dispensed with) consists essentially of a burner *l*, an oil reservoir *m*, and the chimney *K'*, which, if made of metal, should have an opening *n* on one side, covered with a piece of transparent mica, through which the flame 40 may be easily inspected.

The heat from the lamp or heating apparatus is regulated automatically by means of a damper *N*, suspended immediately above the open top of chimney *K'*, upon the outer end 45 of a long rod or lever *O*, having its fulcrum, at *p*, upon a bearing *P*, fastened upon the roof *C* and provided at its other end with an adjustable weight or counterpoise *Q*. Upon a cleat or bracket *r*, fastened on the inside of 50 the back wall *F*, in the open air-space between said back *F* and the adjacent side of the water-tank *H*, is located a thermostat, *R*, of any approved construction, the movable arm *R'* of which is connected to the weighted end 55 of lever *O* by a rod *S*, which passes up through an aperture in the roof, and may be adjusted, as to length, so as to (in connection with the counterpoise *Q*) properly adjust the position 60 of the damper or heat regulator *N* relative to the lamp-chimney *K'*. The water from tank *H* may be emptied, when desired, through a

pipe *T*, which extends through one of the sides *B* and has a faucet *t*, at its outer end.

Each compartment *E* is provided with a false bottom, in the nature of a removable 70 shallow tray *U*, surrounded by raised sides or flanges *u* and sliding in narrow slots between the stationary true bottom *A* and the lower ends of the inclined glass doors *D' D'*; each tray having a knob or handle *v*, so that it may 75 readily be taken out for cleaning, &c., and re-inserted. The bottom of these trays, when the apparatus is in use, should be covered with a layer of clean sand, earth, bran, or a mixture of these ingredients, or some similar 80 inexpensive, absorbent material.

On the inside of each of the sides or end-pieces *B B* is located a ventilator, consisting of a vertical chute or duct *W*, open at both top and bottom, and terminating at its lower 85 open end a short distance above the false bottom or sliding tray *U* while the upper end impinges against the under side of the roof *C*, which is cut through so as to form an opening or outlet, *c*, for the ventilator-chute. By 90 this construction and arrangement of the ventilators, at opposite ends of the brooding-chambers, in conjunction with the screen-partitions *G* and openings *g* at the top of the latter, I provide for a continuous flow of fresh 95 air through the brooding-chambers; there being a constant downward flow of fresh air, heated to the proper temperature by means of the hot-water tank *H*, while the impure and vitiated air escapes upward from the 100 brooding-chambers *E E* through the vertical air-ducts *W W*.

By constructing the hot water tank *H* with a top *h'* overlapping the body of the tank on all sides, so as to form top flanges, the latter 105 will act as deflectors for the heated air, deflecting it, (as it arises around the sides and under the bottom, *h* of the tank) down into the interior space of the brooding-chambers *E E*; the thermostat *R* gyrating automatically 110 to keep this heated air at a constant predetermined temperature, which may be regulated at will by adjustment of the counterpoise *Q* on lever *O*, which as we have seen, 115 regulates the heat-regulating damper *N*.

Having thus described my invention, I claim and desire to secure by Letters Patent of the United States—

1. In a brooding apparatus, the combination with the brooding chambers provided 120 with removable bottom trays and separated from one another by transverse screen partitions leaving open spaces at the top, the water tank located above said brooding chambers, the lamp, the pipe communicating therewith and passing through said tank, of the thermostat, the lever having an adjustable weight at one end and provided with a downwardly depending rod at the other end, the damper connected with said rod, and the rod 125 adjustably connecting said lever with the thermostat, substantially as described. 130

2. In a brooding apparatus the combination with the brooding chambers, separated from one another by screen partitions leaving open air spaces at the tops of said partitions, the heating tank located above said brooding chambers, the lamp, the pipe communicating therewith and passing through said tank, the thermostat, the lever having an adjustable weight at one end and provided with a downwardly depending rod at the other end, the damper connected with said rod, and the rod adjustably connecting said lever with the thermostat, of the end ventilators consisting of vertical ducts or air chutes opening up at

their lower ends near the bottom of the end chambers, to the sides of which they are affixed and impinging with their open upper ends against the apertured top or roof of the apparatus, said apertures forming outlets for the ventilator ducts, substantially as described and for the purpose specified.

In testimony that I claim the foregoing as my own I have hereunto affixed my signature in presence of two witnesses.

LOUIS C. BILLINGS.
